CLAIM

The ornamental design for a lever arm of motorcycle gear shift lever, as shown and described.

DESCRIPTION

FIG. 1 is a perspective view of the lever arm showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view illustrating that the lever arm is pivotally connected to a pedal part of the motorcycle gear shift lever.

Portions of the lever arm illustrated by the broken lines shown in FIGS. 1 to 8 form no part of the claimed design. The broken lines illustrating the pedal part shown in FIG. 8 are for illustrating environmental structure only and form no part of the claimed design.

The dash-dot broken lines in the drawings illustrate boundaries for the claimed design and form no part thereof.
